DESIGN FOR A PRINTED TEXTILE FABRIC OR SIMILAR ARTICLE

Charles F. Scholle, New York, N. Y.

Application April 1, 1937, Serial No. 68,506

Term of patent 3½ years

To all whom it may concern:

Be it known that I, Charles F. Scholle, a citizen of the United States, residing in the city of New York and State of New York, whose post office address is 440 Fourth Avenue, city of New York, county of New York, and State of New York, have invented a new, original, and ornamental Design for a Printed Textile Fabric or Similar Article, of which the following is a specification, reference being had to the accompanying drawing, forming a part thereof.

The figure is a plan view of a printed textile fabric embodying my new design.

I claim:

The ornamental design for a printed textile fabric or similar article as shown.

CHARLES F. SCHOLLE.
